PROCESS FOR CONVERTING HYDROCARBON OILS

Filed April 2, 1940

UNITED STATES PATENT OFFICE

2,340,814

PROCESS FOR CONVERTING HYDRO-CARBON OILS

Rex E. Lidev, Portland, Oreg.

Application April 2, 1940, Serial No. 327,470

4 Claims. (Cl. 196—52)

This invention relates to an improved catalytic process for the conversion of hydrocarbon oils to gases containing large proportions of olefines and liquids in the motor fuel boiling range having a high octane number and a high octane blending value.

An object of the invention is to provide a novel process for the gasification of hydrocarbon oils, yielding as by-products, liquids in the gasoline boiling range which possess high octane numbers and high octane blending numbers, and are valuable as motor fuel or as blending fluids for the improvement of motor fuel.

Another object is to provide a catalytic process for the production in high yields of ethylene and other short chain carbon compounds in the ethylene series, from hydrocarbon oils, together with high B. t. u. gas suitable for use for heating, cooking, or fuel, together with liquid by-products of the type heretofore mentioned.

Another object is to provide a commercially practical process for converting relatively low grade oils into more valuable products.

Another object is to provide a catalytic conversion process of the type above indicated having novel and improved combinations of steps and conditions of operation.

Another object is to provide a catalytic process of the above type which is capable of utilizing various charging stocks for the production of fuel gases, gaseous olefines and aromatics or liquids of the type above mentioned.

Another object is to utilize a suitable catalyst for use in the above process, which is not deleteriously affected either itself or in its ability to act catalytically for the process by the presence of varying amounts of steam.

Various other objects and advantages will be apparent as the nature of the invention is more fully disclosed.

The present process, with suitable changes in operating conditions, is adapted to convert hydrocarbon charging stocks of various characteristics such as, for example, a gasoline fraction or a gas oil fraction from crude petroleum or recycle stock, or topped crude, into products containing hydrocarbon gases, gaseous olefines and a liquid fraction in the motor fuel boiling range, rich in the aromatics benzol, toluol and xylol, from which these aromatics may be separately obtained, or which in its entirety may be used as a motor fuel or as a motor fuel blending agent, or containing a liquid fraction in the motor fuel boiling range chiefly distinguished by its high octane and octane blending numbers and 55

useful as a motor fuel or a motor fuel blending agent.

In accordance with the present invention, the charging stock is first heated to a temperature to completely vaporize the same under conditions such that substantially no cracking takes place. If the nature of the charging stock is such that it cannot be completely vaporized under these conditions, the material may be passed to a flash chamber and separator for removing the non-vaporizable portion. The vapors only are then passed into the conversion zone wherein they are contacted with a suitable catalyst under conditions of temperature, pressure and space velocity which favor the formation of the desired products.

The conversion zone, in one embodiment, comprises a plurality of tubes containing a catalyst, which are externally heated by suitable means to supply the necessary heat for raising the vapors to the desired outlet temperature.

The portion of the charge converted to gases is generally dependent upon temperature, a greater gas yield being obtained at higher temperatures. The gas yield is also related to the space mass velocity and the pressure in the converter unit, decreasing as the space mass velocity increases, and to a lesser extent, decreasing as the pressure increases. The gas composition in general is but little affected by temperature or space mass velocity, but the liquid composition is affected, the liquid becoming less aromatic with increasing space mass velocity and decreasing temperature.

Inasmuch as the reactions are essentially in the vapor phase, when the feed to the converter system is constant the pressure affects both the space mass velocity and the related factor, the contact time of hydrocarbon vapors with the catalyst in the conversion zone. I have found that aside from the changes exerted by pressure because of its effect on the contact time, it exerts an independent effect on the nature of the products as a result of the changes it induces in the equilibria of the reactions in the conversion zone. In general, the yield of olefines and particularly the yield of ethylene, decreases as the pressure increases and to a very much lesser extent the liquids tend to become more aromatic. It is obvious, of course, that the effect of changes in pressure on the contact time and the resultant effect on the products can be eliminated by a proper selection of flow rate or by other methods which will be made clear hereinafter. Consequently, by suitable control of these factors,

among others, it is possible to vary, within limits, the proportion of fuel gases, gaseous olefines, motor fuel and aromatics in the final product.

The vapors leaving the conversion zone are immediately cooled to a temperature suited to stop the reactions, which may involve conversion or cracking or both, before the formation of undesired products takes place. In one embodiment of the present invention this is accomplished by introducing into the vapor stream a quench oil which is derived from a later stage of the process. The quench oil is preferably of such a nature that it does not crack or coke under the conditions to which it is subjected, leaves no residue and introduces no undesirable constituents which require additional steps or apparatus for their subsequent removal.

The vapor stream, after quenching, contains the desired products and the hydrocarbon used for quenching and may be treated in a suitable manner for the removal of the higher boiling residues and the subsequent separation of the gaseous olefines, the fuel gases and the motor fuel fraction. The olefines may be further separated into their components such, for example, as ethylene, propylene and butylene if desired. The liquid boiling in the motor fuel range may consist essentially of benzol, toluol and xylol and in its entirety will possess a high octane number and high octane blending number which renders it suitable with but little subsequent treatment for use directly as a motor fuel or as a blending agent for increasing the octane number of other motor fuel. It may also be used as a source for the production of the aromatics benzol, toluol and xylol in pure form. The liquid fraction, depending on the operating conditions above mentioned, may have a smaller proportion of the aforesaid aromatics but will, in any event, be characterized by high octane and high octane blending values which render it, after but little subsequent treatment, suitable for use as a motor fuel or as a blending agent for increasing the octane number of other motor fuel.

Although the novel features which are believed to be characteristic of this invention are more particularly pointed out in the claims appended hereto, the invention itself may be better understood by referring to the following description, taken in connection with the accompanying drawing, in which a specific embodiment thereof has been set forth for purposes of illustration.

In the drawing, the figure represents diagrammatically a converter plant embodying the present invention.

Referring to the drawing more in detail, the charging stock is supplied by a pump 9 through a charge line 10 and heat exchanger 11 to a vaporizer coil 12. In the embodiment shown, this vaporizer coil comprises a bank of tubes 14 in a suitable heater 15 of any standard type, such as a furnace, a flue through which hot combustion gases pass, the convection zone of the converter furnace to be described, a heat exchanger, or the like.

The charging stock is heated in the heater 15 to a temperature such that complete vaporization takes place. It is to be understood, however, that if the nature of the charge is such that complete vaporization without cracking cannot be obtained in the vaporizer coil, the unvaporized portion of the charge may be removed by suitable separating apparatus not shown. The heat exchanger 11 serves to pre-heat the charge prior

to passage to the vaporizer coil. It may, however, be omitted if desired.

The vapors from the heater 15 are passed through a line 16 to the conversion zone, shown as a furnace 17 having therein a plurality of converter tubes 18 which are indicated diagrammatically as vertical tubes arranged in four banks, each having an inlet header 19 and an outlet header 20. It is to be understood that the tubes may extend either vertically or horizontally and that they may be arranged in vertical or horizontal banks. Suitable heating means, such as burners, not shown, may be provided for externally heating the tubes to the desired temperature. Vapors are supplied through the line 16 and a set of inlet valves 21 to the various inlet headers 19. The vapors, after conversion in the tubes 18, are taken from the outlet headers 20 through valves 22 to a line 25 by which they are supplied to suitable separating apparatus, shown as a fractionating column 26.

The cracked vapors emerging from the tubes 18 are immediately cooled to below conversion temperature by introduction of a suitable quench oil into the vapor stream. In the embodiment shown, the quench oil is taken as a side cut from the fractionating column 26 by means of a side cut stripper 27 of any suitable construction. A line 28 supplies the side cut from the stripper 27 to the heat exchanger 11 and thence through a cooler 29, valve 30, line 31, pump 32, line 33 and a plurality of quench lines 34, controlled by individual valves 35, to the various headers 20. The quench oil may be sprayed into the headers in a position to commingle with the vapor stream and to cool the same substantially instantaneously to a temperature below that at which further reaction takes place.

The excess of the side cut taken from the stripper 27, over that required for quenching purposes may pass through a line 36, controlled by valve 37, to storage or for use as fuel oil, or may be recycled as charging stock for the process by means of a pump 38 and a line 39 controlled by a valve 39a. This excess may be removed and recycled either before or after it passes through the heat exchanger 11.

The fractionating column 26 is operated at temperatures and pressures to separate the residue, which may be of the nature of a heavy fuel oil. This residue may be withdrawn from the bottom of the column 26 through a line 40 and a cooler 41 to storage. The overhead vapors, containing the desired products such as the fuel gas, olefine gas and the motor fuel fraction, are passed through a line 45 and a cooler 46 to a separator 47 which is operated at a temperature and pressure adapted to make a primary separation of the gases from the liquid motor fuel fraction, the former being taken from overhead by a line 48 to a suitable gas separating unit and the latter being taken from the bottom of the separator 47 through a line 49 to a treating unit which is adapted to condition the liquid for use as a motor fuel or as a blending agent or it may be taken if desired when it is largely aromatic, to subsidiary equipment designed for the separation therefrom of the aromatics toluol, benzol and xylol. A portion of the liquid may be returned by a pump 50 and a line 51 to the top of the fractionating column 26 as reflux for temperature control purposes.

Steam and air for reactivating the catalyst may be supplied from a steam line 55 and an air line 56 respectively, controlled by valves 57 and

58, through a line 59 to a coil 60, which may constitute a preheater or superheater coil, in the heater 15, thence through a line 61 and branch lines 62, controlled by individual valves 63 to the supply headers 19. The outlet headers 20 may be connected to a blow down line 64 through lines 65 and valves 66.

When a bank of tubes is to be reactivated, the corresponding valves 21, 22 and 35 are closed to remove the bank from the vapor stream and to interrupt the supply of quench oil to the outlet header 20. By opening the valves 63 and 66 associated with the bank to be reactivated, and by suitable control of the valves 57 and 58, air and steam may be supplied to the tubes from lines 55 and 56 in regulated quantities as required for reactivation purposes and the reactivation products may be removed through the blow down line 64.

In carrying out the present process for the conversion of a charging stock within the gasoline boiling range (100° F. to 380° F.) or a charging stock, such as gas oil (330° F. to 750° F.) which contains no non-volatile reject, the charge may be heated in the vaporizer coil to a temperature of 650° F. to 850° F. at a pressure varying from a partial vacuum to about 150 lbs., the particular temperature and pressure conditions being selected so that no substantial cracking will take place prior to the conversion step. In the event that the charging stock is a topped crude, or a recycle stock containing a fraction which cannot be vaporized without cracking at the above temperatures, the latter is removed by passing the vapors through a suitable flash chamber or other separation means.

The vapors from the vaporizer coil or from the flash chamber are passed directly into the conversion unit where they are contacted with the catalyst in the tubes 18 under conditions of temperature, pressure and space mass velocity adapted to favor the formation of the desired product. It has been found that with 2½" tubes 15' long, with an outlet temperature of between 1150° F. and 1500° F. and at pressures between sub-atmospheric and about 50 lbs. per sq. in., the flow rate or space mass velocity may vary from 1 to 10 units, a unit being defined as the velocity required to pass 62.4 lbs. of oil per hour per cu. ft. of catalyst space. This velocity may, for example, result in a time of contact with the catalyst of from 0.2-3.0 seconds, depending upon the porosity of the catalyst and the percentage of free space in the tubes.

It will be readily apparent that some finite time will be required to bring the oil vapors in the conversion zone from the temperature of approximately 850° F. at which they enter, to a final temperature within the limits of 1150-1500° F. The vapors may be made to attain a temperature in excess of the desired final temperature in their passage through the first 10-15% of the conversion zone but a point is then reached at which an extremely rapid drop in the vapor temperature takes place, to a temperature well below the desired final outlet temperature, despite the fact that heat in large quantities is constantly supplied to the conversion zone. Following this rapid drop, the vapor temperature then rises to the desired final temperature and the vapors can then be made to complete their passage through the conversion zone at temperatures within 50° F. plus or minus of the desirable final outlet temperatures. The period of rapid temperature drop is normally completed by the time the vapors

have travelled through the first 40% of the conversion zone. It is likely that the zone in which the fall in vapor temperature occurs represents that zone in which gasification takes place most rapidly with consequent rapid absorption of the endothermic reaction heat by the vapors. It is possible, by controlling the rate of heat input at various parts of the conversion zone, to fix the peak temperature attained by the vapors before the point of rapid temperature drop is reached, and also to fix the shape of the temperature curve in the last 50% of the conversion zone.

In its preferred embodiment the present process should be provided with a heat input into the conversion zone of such a type that a temperature well in excess of the desired final temperature is attained before the point of rapid temperature drop is reached, and such that, following the temperature drop, the vapors again rise to the desired outlet temperature as rapidly as possible and remain at that temperature for the balance of the time they are in the conversion zone. However, the present invention is not intended to be limited to use with such heat input, but for ease of practical design the temperature gradient may be varied as desired to produce the optimum average temperature.

An important feature of the present invention resides in the elimination of the necessity for careful control of temperatures along the conversion zone, it being required only that the vapors be passed through the zone under conditions of contact time and pressure herein disclosed, and made to attain by the end of the passage a temperature in the range 1150-1500° F., in accordance with the products desired.

It should be further understood that any limiting control tending to maintain the vapor temperature below the final temperature in the first half of the conversion zone is not ordinarily desirable.

The percentage of olefines and the relative proportion of the different olefines is influenced by the selection of the catalyst as well as by the other factors above mentioned. The catalysts selected will accordingly depend upon the product desired. It is to be understood that the term "catalyst" is used in a broad sense and is not intended as a definition of the action of the material. The material may act as a true chemical catalyst to promote the reaction or may act mechanically by surface contact or in various other ways. It has been found that the presence of certain substances favors the formation of certain products and these substances are herein, for convenience, called catalysts.

I have found that silicon carbide is particularly suited to act as a catalyst for the above process. This material aids the conversion of the hydrocarbon oil to gases containing a high proportion of olefines and enhances, though to a lesser extent, the formation of aromatics when the process is carried out in the higher temperature ranges. In its preferred form, the silicon carbide may be present in the form of irregularly shaped porous particles which have been obtained by binding fine mesh silicon carbide powder with about 20% to 25% of ceramic cement which is, itself, catalytically inert. Binding, of course, may be accomplished by light temperature treatment of the mixed powders. A suitable removable filler may be added to the composition before the silicon bond is formed in order to insure a high degree of porosity in the finished product. The bonding may also be accomplished by molding or

extruding the powder by suitable methods, or 5
ceramically by other procedures than the one
above outlined.

The silicon carbide may also be used in the
form of non-porous grains of the proper size or
as non-porous grains formed by appropriate
bonding of silicon carbide powder. The material
may also be used, where desired, as pellets
formed in any of the above mentioned fashions.
Silicon carbide is particularly desirable as a catalyst
for this process because of its strength, and
because of its inertness towards steam and oxygen
at the high temperatures employed and at the
even higher temperatures encountered during the
regeneration procedure.

Various other catalysts may also be used in,
the present process, such as; difficultly reducible
metal oxides in active form, preferably supported
on a suitable carrier such as silicon carbide;
metals in such form as to be catalytically inert
for the decomposition of hydrocarbons to carbon
and hydrogen, etc. The catalyst selected will depend
upon the operating conditions and the other
requirements of the operations involved as well
as upon the product to be obtained.

The tubes are filled with the selected material
and suitable provision is made to retain the catalyst
in place. Preferably, the catalyst is used in
grains of various mesh sizes which are themselves
either porous or non-porous and which are so
disposed within the tube as to create a maximum
of turbulence and surface contact. The selection
of the size of grain to be used will depend upon
a number of factors, among which may be mentioned
the length and diameter of the catalyst bed,
the rate of flow to be employed and the permissible
pressure drop through the catalyst bed, the latter
having an effect upon the total pressure in the system
and consequently, as elsewhere explained, on the nature of the products obtained.
The tubes themselves should be made of a material
which does not interfere with the catalytic
cracking of the vapors therein and which does
not, itself, catalytically direct the cracking into
undesirable directions. Tubes comprising an alloy
18% chromium, 8% nickel, and the remainder
for the most part iron, have been found to be
satisfactory, but it is not intended that the invention
is limited to use with such tubes.

The quench oil is introduced into the outlet
headers to cool the vapors below the reaction
temperature as soon as the desired reaction has
taken place. With an oil of the above type, the
vapors should be cooled to a temperature of from
650° F. to 750° F. In the embodiment shown in
the drawing this is accomplished by injecting
an oil spray into the outlet headers 20. It is to
be understood, however, that this is merely for
purposes of illustration and that the oil may be
introduced at other points and in other ways or
the vapors may be bubbled through an oil bath.
In any event, the arrangement is such that the
vapors are cooled rapidly before undesirable
actions take place.

In the embodiment shown, the quench oil comprises
a side cut taken from the fractionating column 26.
This side cut may constitute a fraction
within the gas oil boiling range which, having already
been subjected to conversion conditions,
will not, under the conditions prevailing in the
quenching zone, readily further crack or coke,
which vaporizes at the temperature of the vapor
stream without leaving a residue and which introduces
no undesirable constituents which require special
steps or apparatus for their subse-

quent removal. It is to be understood, of course,
that other quench oils may be employed if desired
in any particular instance. The quench oil
is shown as cooled by heat interchange with the
charging stock for purposes of heat conservation.

The vapors entering the fractionating column
contain the gaseous olefines, fuel gas, a minor
amount of other permanent gases, the motor fuel
fraction and heavier residues. The fractionating
column may be operated under suitable
conditions of temperature and pressure to separate
the residue, which is withdrawn from the
bottom as a heavy fuel oil, and, where desired,
to separate as a side cut material in the gasoline
and gas oil boiling ranges suitable for use as a
quenching stock or as recycle stock, or as light
furnace oil. The overhead vapors containing the
permanent gases and the motor fuel fraction may
be treated at a suitable temperature and pressure
in the separator 47, to effect a primary separation
of the permanent gases and liquid fractions.
The gases will contain the desired olefines such as
ethylene, propylene and butylene, and the fuel
gases such as hydrogen, methane, and ethane,
together with minor amounts of liquid hydrocarbons
having high vapor pressures, such as
amylene, benzol, hexylene, etc., which may be
present as unseparated vapors. These various
constituents may be separated by any suitable
means not shown. The liquid fraction may be
treated to condition it for use as a motor fuel or
as a blending agent for improving the octane
number of other motor fuels or when it is produced
under conditions which make it highly
aromatic, it may be treated to separate therefrom
the aromatics such as benzol, toluol and xylol, and
other materials or mixtures of materials suitable
for various purposes.

In carrying out this process, it has been found
that periodic regeneration of the catalyst is required,
probably because of carbon deposition thereon.
The converter tubes are accordingly arranged
so that one of the banks may be removed
from the stream and regenerated while the process
is continued with the remaining banks.
In regenerating the catalyst, after the converter
tubes have been removed from the stream they
are preferably first blown with dry steam to remove
any residual vapors and to prevent the
formation of explosive mixtures therein.
Thereafter, a suitable mixture of dry steam and air
may be supplied to burn out the carbon,
the quantity of air being controlled so as to avoid an
excessive rate of combustion. The tubes may or
may not be removed from heat transfer relationship
with the furnace during this part of the process.
After the carbon has been completely
burned out, the tubes may again be blown with
dry steam to remove residual air before being
returned to stream.

The air or the air and steam mixture may be
preheated or the steam mixtures may be superheated
in the coil 60 so as to prevent cooling the
tubes to below reaction temperatures during reactivation
and also to prevent introduction of moisture
into the system or into contact with the hot
catalyst, which might result in tube ruptures.

By the use of four banks of catalyst tubes, it
will be noted that three banks are always on
stream, that is, three-fourths of the converter
capacity is always in productive use. Obviously,
if the number of banks is increased the relative
proportion of banks in productive use will be increased.
Four banks have been shown merely
for purposes of illustration. This system of cat-

alyst control results in a substantially continuous conversion process in which the flow of products is not interrupted or greatly disturbed during reactivation periods.

In a specific embodiment of the invention, utilizing Michigan gas oil of about 39 gravity and operating to favor the production of ethylene, the charging stock may be supplied to the vaporizer coil 12 at a temperature of about 80° F. and a pressure of 100 lbs. per sq. inch. In the vaporizer coil the temperature may be raised to about 800° F. and the vapors supplied to the inlet headers 20 at about 60 lbs. pressure for distribution to the converter tubes 18 wherein they are contacted with a silicon carbide catalyst. The vapors may leave the converter tubes 18 at an outlet temperature of about 1400° F. and are immediately quenched in the outlet headers 20 to a temperature of about 650° F., at which temperature they are supplied to the fractionating column 26. The fractionating column may be operated at a temperature gradient from top bottom of from 310° to 600° F. and at a pressure of about 24 lbs. The separator 47 to which the overhead vapors from the fractionating column are supplied may be operated at about 90° F. and 20 lbs. pressure.

In another embodiment of the invention, operating the converter at an outlet pressure substantially atmospheric and using the type of charge above specified, the charge may be raised to a temperature of about 400° in the heat exchanger 11 and to a temperature of about 800° F. in the vaporizer coils 12. The charge may be supplied to the vaporizer coil at 100 lbs. pressure and to the converter tubes containing silicon carbide, as above mentioned, at a pressure of about 30 lbs. The converter tubes may have an outlet temperature of about 1400° F. and an outlet pressure of about 5 lbs. The vapors may be quenched to a temperature of about 650° F. and may be supplied directly to the fractionating column 26 as above mentioned.

It is to be understood that the fractionating column is intended to represent diagrammatically a suitable separation apparatus and, if desired, a portion of the fixed gases may be separated prior to the application of the vapor stream to the fractionating column. For the low pressure operation above specified, the fractionating column may be operated at a temperature gradient from top to bottom of from about 230° F. to 500° F. and at a pressure of about atmospheric, the separator 47 being operated at atmospheric pressure and at a temperature of 90° F.

It is to be understood that these examples are given merely for purposes of illustration and that the temperatures and pressures may be varied in accordance with the particular charging stock used and the characteristics of the product which it is desired to obtain.

It may be found desirable to operate the converter unit at a sub-atmospheric pressure so as to favor the production of olefine gases. This may conveniently be accomplished by passing steam or some other inert gaseous diluent with the vapors through the converter tubes so as to reduce the partial pressure of the vapors and obtain effectively sub-atmospheric operating conditions without requiring the use of vacuum equipment. Steam or other gaseous diluent may also be used when operating at other pressures, either sub-atmospheric or superatmospheric for reducing the partial pressure of the hydrocarbon vapors without reducing the total pressure in the system. The water vapor will, of course, be sepa-

rated at a later stage by suitable separator means.

As above described, the pressure on the system exerts changes in the nature of the products obtained for two reasons—one, the result of the pressure as such, and the other, a result of the effect of pressure on the contact time. It is obvious that this second effect can be overcome by the introduction into the vapor stream of steam or some other inert gaseous diluent which will increase the rate at which the gases pass through the conversion zone, and it may be found desirable in order to maintain the contact time independent of the pressure at which the system is operated, to introduce water with the hydrocarbon oil or to introduce steam, or other inert gaseous diluents into the hydrocarbon vapor for this purpose. The water vapor or the other diluents employed will, of course, be separated at a later stage by suitable separator means.

The other inert gaseous diluents may take the form of nitrogen, methane, or carbon dioxide, etc., inert as it is here used, being intended to mean only that the material employed shall be unaffected, and in general takes no part in the reactions at the temperatures employed.

It has been found, in general, that a lower operating pressure changes the gas yield and also increases the difficulty of gas separation because of the large amount of the liquid fraction which is carried along in the gas stream as vapor. It is therefore to be understood that suitable separation apparatus may be required in addition to that set forth in detail in the drawing. Such apparatus forms no part of the present invention and accordingly has not been specifically described.

Using a virgin gas oil of 36-38° A.P.I. gravity boiling between 380° F. and 750° F. with a converter tube outlet temperature of between 1375° F. and 1450° F., the oil processed, depending on the rate of flow, pressure and catalyst, may yield on a once-through basis about the following products:

	Per cent by weight
45 Gas	50-75
Motor fuel	20-10
Recycle stock	24-12
Non-volatile reject	6- 3

	Per cent
Ethylene	26
Propylene	12
Butylene	8

55 and it may contain not more than 45%, by volume, of methane, ethane and hydrogen. The motor fuel fraction will be a liquid rich in aromatics with a gravity in the range of 30-38° A. P. I. and an octane number of from 90-112.

60 If the converter tube outlet temperature is in the range of 1200° to 1375° F., the oil processed may have the following composition:

	Per cent by weight
Gas	20-40
Motor fuel	32-20
Recycle stock	38-32
Non-volatile reject	10- 8

	Per cent
Ethylene	24
Propylene	14
Butylene	6

75 and may contain not more than 49% of methane,

ethane and hydrogen. The liquid boiling in the gasoline range will, in this case, be substantially less aromatic than that produced under the higher temperature conditions of the first example but will be characterized by its high octane values and will be suitable for use either directly as a motor fuel or as a blending agent for improving the octane number of motor fuels. It will have an octane number in excess of 75, and a blending value in excess of 90.

The above are given as examples only and it is to be understood that other variations in operating conditions will produce products having other compositions.

While the novel cooperative relationship between the various steps of the process combine to effect an improved, efficient and commercially practical conversion unit, many of the novel features are adaptable to use in other combinations and in other types of cracking processes and for the treatment of other materials. Various other features and advantages of the invention, both in the individual steps and in the various combinations thereof will be readily apparent to those familiar with the oil treating art. It is accordingly to be understood that the invention is not to be restricted to the specific embodiments herein set forth, but is only to be restricted in accordance with the scope of the following claims.

What is claimed is:

1. The process for converting hydrocarbon oil charging stock into products containing a large proportion of gaseous olefines, the balance being fuel gas and a liquid fraction in the motor fuel boiling range having a high octane number and a high octane blending value, which comprises supplying hydrocarbon vapors to a conversion zone comprising a plurality of parallel connected, externally heated paths containing a silicon carbide catalyst and terminating individually in a common transverse outlet path forming a header, heating the vapors in said conversion zone to a conversion temperature suited to the formation of the above mentioned products, injecting into the vapors in said outlet header a quench oil suited to cool the vapors to a temperature sufficiently low to stop the conversion reaction, and separating the olefinic and motor fuel fractions from the remaining reaction products.

2. The process for converting hydrocarbon oil charging stock into products containing a large proportion of gaseous olefines, the balance being fuel gas and a liquid fraction in the motor fuel boiling range having a high octane number and a high octane blending value, which comprises supplying hydrocarbon vapors to a conversion zone comprising a plurality of parallel connected, externally heated paths containing a silicon carbide catalyst and terminating individually in a common transverse outlet path form-

ing a header, heating the vapors in said conversion zone to a temperature between 1150° F. and 1500° F. and at an outlet pressure of not more than 50 pounds per square inch while passing the vapors through said zone at a velocity to maintain a contact time therein of between about 0.2 to 3.0 seconds to form the above mentioned products, injecting into the vapors in said outlet header a quench oil suited to cool the vapors to a temperature between about 650° F. and 750° F. to stop the conversion reaction, and separating the olefinic and motor fuel fractions from the remaining reaction products.

3. The process for converting hydrocarbon oil charging stock into products containing a large proportion of gaseous olefines, the balance being fuel gas and a liquid fraction in the motor fuel boiling range having a high octane number and a high octane blending value, which comprises
- 15 heating said stock in a vaporizing zone to a vaporizing temperature, supplying vapors from said vaporizing zone to a conversion zone comprising a plurality of parallel connected, externally heated paths containing a silicon carbide catalyst and terminating individually in a common transverse outlet path forming a header, heating the vapors in said conversion zone to a conversion temperature suited to the formation of the above mentioned products, injecting into
- 20 the vapors in said outlet header a quench oil suited to cool the vapors to a temperature sufficiently low to stop the conversion reaction, supplying the conversion products to a fractionating zone, withdrawing the olefinic and motor fuel
- 25 fractions as a vapor from the top of said fractionating zone, separating the olefines from said motor fuel fraction, withdrawing a side cut from said fractionating zone and supplying the same for use as the quenching oil above mentioned.
- 30 4. A system for converting hydrocarbon oils for the production of products containing large proportions of gaseous olefines, the balance being fuel gas and a liquid fraction in the motor fuel boiling range having a high octane number and a high octane blending value, which comprises a converter furnace having at least one bank comprising a plurality of parallel connected, externally heated converter tubes containing a silicon carbide catalyst and terminating in a common
- 35 45 outlet header, means for supplying hydrocarbon vapors to said converter tubes, means for heating the vapors therein to a conversion temperature suited to the formation of the above mentioned products, means for injecting into the vapors in said outlet header a quench oil suited to cool the vapors to a temperature sufficiently low to stop the conversion reaction, and separating means to separate the olefinic and motor fuel fractions from the remaining reaction products.
